UNITED STATES PATENT OFFICE.

FRED A. READ, OF LYNN, MASSACHUSETTS, ASSIGNOR TO THE REECE BUTTON HOLE MACHINE COMPANY, OF BOSTON, MASSACHUSETTS, A CORPORATION OF MAINE.

THREAD-CLAMP FOR SEWING-MACHINES.

1,197,234.

Specification of Letters Patent.

Patented Sept. 5, 1916.

Application filed November 19, 1914. Serial No. 872,902.

To all whom it may concern:

Be it known that I, FRED A. READ, a citizen of the United States, residing at Lynn, county of Essex, State of Massachusetts, have invented an Improvement in Thread-Clamps for Sewing-Machines, of which the following description, in connection with the accompanying drawing, is a specification, like characters on the drawing representing like parts.

This invention has for its object to provide a novel thread clamp for holding the end of the needle thread so that when the stitching operation is started the first stitch will be properly formed without danger that the end of the needle thread will be drawn through the fabric.

My invention is capable of use with sewing machines of different types, but I have herein illustrated it as it might be embodied in a so-called "Reece" buttonhole sewing machine. Examples of the "Reece" buttonhole sewing machine may be found in the following United States Letters Patent: No. 25 494,280, March 28, 1893; No. 655,637, August 7, 1900; No. 1,019,677, March 12, 1912.

Buttonhole sewing machines of this type embody work-holding means in which the work is clamped, and stitch-forming mechanism including upper thread mechanism and complementary under thread mechanism by which the buttonhole stitches are formed, said stitch-forming mechanism being carried by a suitable frame. When the machine is set in operation, the work-holding means and stitch-forming mechanism have a movement relative to each other to bring the stitch-forming mechanism and work-holding means into such relative position that the stitches will be properly formed on the buttonhole, this being referred to as the stitching position, and during the stitching operation said work-holding means and stitch-forming mechanism have a further relative movement which is in the nature of a feeding movement to cause the stitches to be progressively made along the edges of the buttonhole. When the buttonhole has been completed, the stitch-forming mechanism is brought to rest, and said stitch-forming mechanism and work-holding means have a further relative movement to bring the parts into their initial position.

Sewing machines of the above type are provided with buttonhole-cutting mechanism

which operates to cut the buttonhole either before or after the stitching operation. The cutting of the buttonhole is accomplished when the stitch-forming mechanism and work-holding means have a relative position different from that in which the stitching operation is performed, and which position will be referred to as the buttonhole-cutting position.

When the machine has been brought to rest at the end of the stitching operation, the stitch-forming mechanism and work-holding means are in buttonhole-cutting position, and when the machine is first started, the work is clamped by the work-holding means, and if the machine is one which cuts the buttonhole before the stitching operation, the buttonhole will be cut, after which the stitch-forming mechanism and work-holding means have a relative movement to bring the parts into stitching position. The stitch-forming mechanism is then set in operation and said stitch-forming mechanism and work-holding means have a relative feeding movement to provide for the formation of the edge stitches around the buttonhole, and when the stitching has been completed, the stitch-forming mechanism is brought to rest and said stitch-forming mechanism and work-holding means have a further relative movement to carry them into buttonhole-cutting position again, at which time the machine is brought to rest.

When the stitching operation is first started it is customary for the operator to hold the end of the upper thread which is controlled by a needle while the first stitch is being formed in order that at the first thrust of the needle a loop may be properly formed in the upper thread with which the under thread may be concatenated. If the end of the upper thread is not held either by the operator or some suitable means it frequently happens that the said end will be drawn through the cloth, thus destroying the loop with which the under thread is to be concatenated. If this occurs the first stitch will be spoiled. I have provided herein a novel device by which the end of the upper thread may be held during the formation of the first stitch, and in the selected embodiment of my invention this thread-holding device is associated with the work clamp, although this is not essential to the invention.

In order to give an understanding of my invention I have illustrated in the drawings a portion of a buttonhole sewing machine of the "Reece" type to which my invention is applied.

Figure 1 is a side view of a portion of the stitch frame and clamp frame of a so-called "Reece" buttonhole sewing machine; Fig. 2 is a fragmentary plan view showing the 10 thread holder associated with the thread clamp; Fig. 3 is a perspective view of the thread holder detached; Fig. 4 is an enlarged section on substantially the line α — α , Fig. 3.

In the sewing machine herein illustrated, 15 the stitch-forming mechanism is sustained on a frame 1 which for convenience will be hereinafter referred to as the stitch frame. This stitch-forming mechanism includes the usual upper thread mechanism in the form 20 of a reciprocating needle bar 2 carrying an eye-pointed needle, and also includes complementary under thread mechanism which is not herein illustrated as it is not necessary to give an understanding of the invention.

The work-holding means is herein shown 25 in the form of a clamp frame 3 on which the work is supported and work clamps 5 that are supported by arms 4 that are pivotally secured to the clamp frame 3 to 30 permit the clamps to move toward and from the clamp frame thereby to clamp and unclamp the work. The stitch frame 1 with its stitch-forming mechanism and the work-holding means are constructed to be moved 35 relative to each other, as above described, to move the parts from buttonhole-cutting position to stitching position and vice versa, and also to provide the necessary feeding movement during the stitching operation. 40 The means for giving the parts such relative movement are or may be all as illustrated in the above-mentioned patents and hence I have not deemed it necessary to further illustrate or describe it herein.

The sewing machine herein shown is also 45 provided with a needle thread cutter 6 which is mounted on a rock-shaft 7 journaled in bearings 8 carried by the stitch frame, said rock-shaft being provided with an arm 9 which is engaged by a finger 10 formed on 50 the gear 11 by which the upper thread mechanism is rotated thereby to cause the cutter 6 to sever the upper thread at the end of the stitching operation on a buttonhole. This thread cutter is similar to that 55 illustrated in United States Patent No. 1,153,148, dated September 7, 1915, but as it forms no part of the present invention, further description thereof is not necessary.

Fig. 1 illustrates in full lines the relative 60 position of the stitch-forming mechanism and work-holding means at the time that the sewing machine is at rest, this position being referred to as the buttonhole-cutting 65 position. When the machine is first started,

the work clamps 5 are brought into engagement with the work to hold it firmly while the buttonhole is being stitched, and if the machine is equipped with a buttonhole-cutting device that is designed to cut the buttonhole before the stitching operation, such cutting device will be actuated to perform its duties. The stitch frame and the work-holding means are then given a relative movement to carry them from buttonhole-cutting into stitching position, and when they are in stitching position the stitch-forming mechanism is set in operation thereby to form the edge stitches of the buttonhole. The dotted line position in Fig. 1 70 shows the relative position of the stitch-forming mechanism and the work-holding means when they are in stitching position. When the stitch-forming mechanism is set in operation the upper and under thread mechanism will operate on the work held by the work clamps to concatenate the edge stitches of the buttonhole, during which time the stitch frame and work-holding means or clamp frame are given a relative feeding 75 movement. When the stitching has been completed around the buttonhole, the stitch-forming mechanism is brought to rest and at this time the stitch-forming mechanism has a position relative to the clamp frame 80 indicated approximately by the dotted line position Fig. 1. Thereafter, the stitch frame with its stitch-forming mechanism and the clamp frame or work-holding means have a further relative movement to bring the parts 85 into buttonhole-cutting position which is indicated by the full lines in Fig. 1. It is during this latter relative movement of the stitch frame and the clamp frame or work-holding means from stitching to buttonhole-cutting position that the thread cutter 90 95 is operated to sever the needle thread beneath the clamps 5 which it will be understood has been raised from the work after the buttonhole has been stitched.

My improved thread clamp is designed to seize and clamp the portion 13 of the upper thread 12 which extends between the needle and the work just after the completion of the stitching operation on any buttonhole 100 and while the stitch frame and clamp frame or work-holding means are having their relative movement from stitching to buttonhole-cutting position. My thread clamp is also preferably designed to hold the needle 105 thread after it has been severed and until the stitching operation on the next buttonhole begins, thus enabling the first stitch to be perfectly formed without any waste of thread such as results when the operator 110 draws out the end of the needle thread to hold it. The thread clamp as herein shown comprises a body portion 14 adapted to be secured to one of the clamps 5, said body portion having for this purpose a laterally 115 120 125

extended perforated ear 15 which overlies one of the clamps 5 and is secured thereto by means of a screw 16. The body portion 14 extends longitudinally and it carries a 5 resilient clamping member 17 in the form of a flat leaf spring. This leaf spring is secured to the body 14 at one end by some suitable means as the screw 18 and the opposite end 19 thereof is flared outwardly slightly 10 thereby to form with the curved or beveled surface 20 a flaring throat into which the end 13 of the needle thread can enter. 21 is an adjusting screw which is screw-threaded into the body 14 and engages the plate 17 15 thereby to limit the movement of the clamping plate toward the body and to regulate the clamping pressure of the clamp on the thread.

When the sewing machine is in operation 20 stitching the buttonhole the needle for the upper thread is operating in the position shown in dotted lines Fig. 1 which is in the rear of the thread clamp. When the buttonhole stitching has been completed, the 25 stitch frame and clamp frame have the relative movement above referred to to bring the parts into the full line position Fig. 1, and during this movement the portion 13 of the upper thread 12 which extends from the 30 needle to the work will be carried into the flaring throat of the thread clamp formed by the portion 19 and curved edge 20 and will be carried into the space between the plate 17 and the body 14 and thereby 35 clamped. The knife 6 is then operated to sever the thread below the clamp and the clamp retains its grip on the severed end of the thread while the machine is brought to rest and until the machine is set in operation again and the first stitches of the next 40 buttonhole are formed. The grip of the clamp on the end of the needle thread is sufficient to cause the first stitch of the next buttonhole to be properly formed, and as the 45 stitching on the next buttonhole continues the end of the thread will be pulled out from the clamp, as will be obvious. The adjusting screw 21 provides, as stated above, for regulating the clamping pressure on the 50 end of the thread to correspond to the tension on the thread and the size of the thread, etc.

While I have illustrated herein a selected embodiment of my invention, I do not wish 55 to be limited to the constructional details shown, as the form which the invention assumes may be varied, and the manner in which it may be applied to sewing machines 60 may also be varied, depending on the character of the machine.

I claim:

1. In a buttonhole sewing machine, the 65 combination with stitch-forming mechanism, of work-holding means, said stitch-forming mechanism and work-holding

means having a movement relative to each other subsequent to the completion of the stitching operation on a buttonhole to bring the parts from stitching to buttonhole-cutting position, and a needle thread clamp 70 carried by the work-holding means and located in such a position that the needle thread is drawn into said clamp during the relative movement of the parts from stitching to buttonhole-cutting position. 75

2. In a sewing machine, the combination with a stitch frame carrying a reciprocating needle, of a clamp frame, said frames having a movement relative to each other in a direction at right angles to the movement of the needle after the needle has been brought to rest upon the completion of a predetermined stitching operation, a work clamp secured to the clamp frame, and a needle thread clamp carried by the work clamp in 80 such a position that said relative movement of the frames will cause the portion of the needle thread extending from the needle to be carried into the thread clamp. 85

3. In a sewing machine, the combination with a stitch frame carrying a reciprocating needle, of a clamp frame, said frames having a movement relative to each other in a direction at right angles to the reciprocating movement of the needle after the needle has 90 been brought to rest upon the completion of a predetermined stitching operation, a work clamp secured to the clamp frame for movement relative thereto, and a needle thread clamp carried by the work clamp and having 95 an open thread-receiving throat positioned so that such relative movement of the frames will cause the portion of the needle thread extending from the needle to the work to be carried into said throat. 100

4. In a sewing machine, the combination with a clamp frame, of a work clamp movably supported thereby, a stitch frame carrying a reciprocating needle and having a movement relative to the clamp frame subsequent to the completion of a predetermined stitching operation, and a needle thread clamp secured to the work clamp and so situated that the needle thread is drawn into it by said movement of the stitch frame. 110

5. In a buttonhole sewing machine, the combination with stitch-forming mechanism and work-holding means having a movement relative to each other subsequent to the completion of the stitching operation on a buttonhole to carry the parts from stitching to buttonhole-cutting position, of a needle thread clamp carried by the work-holding means and presenting an open throat so situated that the needle thread is drawn into 120 it by such relative movement. 125

6. In a sewing machine, the combination with a stitch frame carrying a reciprocating needle, of a clamp frame, said frames having a movement relative to each other after the 130

completion of a predetermined stitching operation, a thread clamp secured to the clamp frame and comprising a body member and a clamping plate resiliently held against the body member and presenting therewith an open throat so situated that the needle thread is drawn into it by such relative movement of the frames, and means to regulate the clamping pressure of the clamp-
10 ing plate.

7. In a sewing machine, the combination with a stitch frame carrying a reciprocating needle, of a clamp frame, said frames having a movement relative to each other after the completion of a predetermined stitching operation, a thread clamp secured to the

clamp frame and comprising a body member and a clamping plate resiliently held against the body member and presenting therewith an open throat so situated that the 20 needle thread is drawn into it by such relative movement of the frames, and a regulating screw carried by the body member by which the clamping pressure of the clamping plate is regulated.

25 In testimony whereof, I have signed my name to this specification, in the presence of two subscribing witnesses.

FRED A. READ.
